PORATABLE SAW TABLE

Walter G. Marsh, Birmingham, Melvin K. Mercier, Detroit, and James J. Rhoads, Westland, Mich., assignors to Tapco Products Company, Inc., Detroit, Mich.

Filed Mar. 9, 1973, Ser. No. 339,850

Term of patent 14 years

Int. Cl. D8—99

U.S. Cl. D8—14

FIG. 2

FIG. 1 is a perspective view of a portable saw table embodying the novel design.

FIG. 2 is a plan view of the same fragmentarily shown for ease of illustration.

FIG. 3 is a front elevational view of the same at an enlarged scale.

FIG. 4 is a right end elevational view of the same at an enlarged scale.

FIG. 5 is a rear elevational view of the same at the scale shown in FIG. 3.

FIG. 6 is a left end elevational view of the same at the scale shown in FIG. 4.

We claim:

The ornamental design of a portable saw table, as shown and described.
